UNITED STATES PATENT OFFICE

WILLIAM D. WHITAKER, OF PHILADELPHIA, PENNSYLVANIA, ASSIGNOR TO DELANY
& COMPANY, INC., A CORPORATION OF PENNSYLVANIA

FEEDING AND DISTRIBUTING DEVICE

Application filed October 5, 1928. Serial No. 310,489.

This invention relates to improvements in a feeding and distributing device adapted for feeding loose material into a machine, and particularly adapted for feeding loose curled hair into an interlacing machine, adapted for interlacing a relatively thick layer of hair for forming fillers for cushions and mattresses.

The object of the invention is to provide a feeding and distributing mechanism for uniformly feeding the hair into the receiving box of a machine, whereby the receiving box will be supplied or filled uniformly with the loose hair throughout the entire width of the receiving box; a further object of the invention is to provide a casing having a small inlet and a relatively large or wide outlet, which is coextensive with the full width of a machine into which the material is being fed; a further object is to provide a blade or blades within the casing for directing the course of the material through the casing; a still further object is to provide suitable mechanism for operating two or more blades in unison, which mechanism is adapted for oscillating the blades for evenly distributing the materials; and a still further object is to provide means for adjusting the throw of the oscillating mechanism whereby the blades may be limited in their oscillating movements and utilized for filling the receiving box when the latter is reduced in width for forming cushions or mattress fillers which are narrower than the full width of the interlacing machine. These together with various other novel features of construction and arrangement of the parts, which will be more fully hereinafter described, constitute my invention.

Referring to the accompanying drawings Fig. 1 is a side elevation of a feeding and distributing device embodying my invention and showing a portion of a machine for interlacing hair; Fig. 2 is a plan view of a portion of Fig. 1, showing the feeding and distributing device; Fig. 3 is a vertical transverse section on line 3—3 Fig. 2; Fig. 4 is a horizontal section on line 4—4 Fig. 3; and Fig. 5 is an enlarged perspective view showing the operating mechanism of the distributing device.

In the accompanying drawings in which like reference characters refer to like parts, 1 represents a casing having top and bottom walls 2 and 3 and side walls 4 and 5 connected with an inlet tube 7, preferably of rectangular formation, which forms the inlet to the casing 1. The side walls 4 and 5 are inclined outwardly from the inlet tube 7, thus providing the casing 1 with an enlarged outlet end 8, which is connected in any suitable manner with a machine 10 which is to be supplied with loose material. Fig. 1 of the drawing shows a portion of a machine 10 for interlacing curled hair, which machine may be of any standard type well known in the art. Such interlacing machines are provided with a receiving box 13, formed by a conveyor belt 14, and an adjustable top wall 15, connecting plates 16 and 17 and adjustable side walls 18, by means of said adjustable parts the width or height of the receiving box may be varied according to the size of the fillers for mattresses or cushions, which are to be formed by the interlacing machine 10.

The inlet tube 7 is connected with the discharging tube 20, of a picker 22, which latter may be of any standard type adapted for picking the material into loose formation and discharging it to the inlet tube 7, from which it is blown by air forced through the curved pipe 24, connected tangentially with the pipe 7 having its opposite end connected with a blower 26, in any suitable manner, adapted for forcing air through the casing 1 and carrying the loose material from the picker 22 through the casing 1 and discharging it into the interlacing machine 10.

The casing 1 is provided with blades 30 and 31 which are movably mounted within the casing and are adapted for directing the flow of air and loose material through the casing for filling the receiving box 13 of the machine 10 and distributing the loose material evenly through the full width of the receiving box.

The distributing mechanism consists of said blades 30 and 31 which are secured upon shafts 33 and 34. Said shafts are pivotally mounted in bearing bars 36 and 37, which are clamped above and below the casing 1 by bolts 38 and 39, located at opposite ends of

the bars 36 and 37. The lower ends of the shafts 33 and 34 extend below the bearing bar 37 and have secured thereto arms 40 and 41, having their outer ends connected together by a link 42 adapted for oscillating the blades in unison.

The link 42 is moved by means of a crank-arm 44 which is adjustably secured in the head 45 of a shaft 46, having secured thereon a worm-wheel 48, which in turn is rotated by a worm 49 secured on a shaft 50, rotated by a belt 51, driven by a pulley 52 secured on the shaft 53 of the blower 26. A frame 54 is rigidly secured to the casing of the blower 26 and to the cross bar 37 and forms bearings for the horizontal shaft 50 and the vertical shaft 46.

The crank-arm 44 is of dove-tail cross section and the head 45 is provided with a dove-tail slot to receive the crank-arm 44 and permit the latter to be adjusted in said head 45, and secured in any adjusted position by a set-screw 47. The outer end of the crank-arm 44 is provided with a pivot-head 61, having a stud shaft 62 which is pivotally mounted in the crank-arm 44. Said head 61 is provided with a slot 63, which extends across the face of the head 61 and is occupied by a guide bar 65 rigidly secured below and at right angles to the length of the link 42. The pivot-head 61 slides freely throughout the length of the guide-bar 65 when the crank-arm 44 is rotated, thus moving the link 42 lengthwise, which in turn moves the arms 40 and 41, thus oscillating the blades 30 and 31.

The pivoted shafts 33 and 34 carrying the blades 30 and 31 are positioned adjacent to the vertical side walls 4 and 5 of the casing 1, and the inlet tube 7 is provided with flaring inner plates 60, shown in dotted lines, Fig. 1, which plates terminate adjacent to the shafts 33 and 34 carrying said blades, so that the material being forced through the inlet tube 7 will be admitted to the casing 1 between the blades 30 and 31.

The operation of the device is as follows, the blades are oscillated continuously during the operation of the blower, which latter is driven by suitable belt connections from the picker. As the blades are oscillated horizontally within the casing 1, the loose material passing through the casing will be directed into the receiving box 13 of a machine 10, and distributed evenly throughout the width of the receiving box, thus uniformly filling the latter with the material.

By adjusting the crank-arm 44 relatively to the head 45, the radius of the pivot-head 61 may be varied relatively to the head 45, thereby changing the distance which the link 42 will move and thus changing the throw of the blades 30 and 31. By this adjusting means the material between the blades may be directed in greater or less quantities at the

center or sides of the receiving box as desired.

Various changes may be made in the details of construction and the operation of the various parts, as above described, without departing from my invention.

I claim:

1. A feeding device having in combination, a casing having inlet and discharge openings, an inlet pipe connected with the inlet of the casing, a material treating machine operatively connected with the inlet pipe for feeding material through the casing, blades mounted within the casing, said blades positioned adjacent to opposite sides of the inlet pipe forming a passageway for the material to enter the casing between the blades, shafts pivotally mounted within the casing upon which the ends of the blades adjacent to the inlet pipe are secured, and means operatively associated with said shafts for oscillating the shafts in unison for directing the flow of material through the casing.

2. A feeding device having in combination, a casing having inlet and discharge openings, a pneumatic feeding device for moving loose material through the casing, an inlet pipe connected with the inlet of the casing and with said feeding device, blades positioned within the casing in spaced relation to each other forming a passageway between them for the material to pass from the inlet pipe through the casing, shafts rotatably mounted upon the casing to which the ends of said blades adjacent to the inlet pipe are secured, arms secured to said shafts without the casing, a link connecting said arms, and means for reciprocating said link for oscillating the blades in unison.

3. A feeding device having in combination, a casing having inlet and discharge openings, an inlet pipe connected with said casing, a material treating device for supplying material through the inlet pipe to the casing, blades mounted in spaced relation to each other within the casing forming a passageway between said blades for the loose material to pass between said blades, shafts rotatably mounted within the casing upon which shafts the ends of said blades located adjacent to the inlet pipe are secured, arms upon said shafts located without the casing, a link connecting said arms, a guide-bar secured upon the link and extending transversely thereof, a pivot-head slidably mounted upon said guide-bar, a crank-arm in which the pivot-head is pivotally mounted, a shaft upon which the crank-arm is mounted, and means for rotating said last mentioned shaft.

4. A feeding device having in combination, a casing having inlet and discharge openings, an inlet pipe connected with said casing, a material treating machine to which the inlet pipe is connected, blades movably mounted within the casing located in spaced relation

to each other forming a passageway for the material to pass between said blades, shafts located within the casing adjacent to the inlet pipe upon which the blades are secured, arms secured upon said shaft, a link connecting 5 said arms, a guide-bar secured upon said link extending transversely thereto, a crank-shaft, a bearing associated with said casing in which the crank-shaft is rotatably mounted, a crank-arm secured upon said crank-shaft, a head pivotally mounted upon the crank-arm, said head slidably mounted upon said guide-bar and adapted for reciprocating the link when the crank-arm is rotated, gearing operatively associated with the crank-shaft for 10 rotating the latter, and means for operating said gearing.

5. A feeding device having in combination, a casing having inlet and discharge openings, 20 an inlet pipe connected with said casing, a material treating machine to which the inlet pipe is connected, blades movably mounted within the casing located in spaced relation to each other forming a passageway for the material to pass between said blades, shafts located within the casing adjacent to and at either side of said inlet pipe upon which the blades are secured, arms secured upon said shafts, a link connecting said arms, a guide-bar secured upon said link extending transversely thereto, a crank-shaft, a bearing associated with said casing in which the crank-shaft is rotatably mounted, a head secured to the crank-shaft, a crank-arm adjustably 25 mounted in said head, a pivot-head pivotally mounted upon the crank-arm operatively associated with said guide-bar, and means for rotating said crank-shaft.

6. A feeding device having in combination, 40 a casing having inlet and discharge openings, an inlet pipe connected with said casing, a material treating machine to which the inlet pipe is connected, blades movably mounted within the casing located in spaced relation to each other forming a passageway for the material to pass between said blades, shafts located adjacent to said inlet pipe upon which the blades are secured, arms secured upon said shaft, a link connecting said arms, a guide- 45 bar secured upon said link extending transversely thereto, a crank-shaft, a bearing associated with said casing in which the crank-shaft is rotatably mounted, a head upon said crank-shaft, said head having a dove-tail slot 50 formed across the face thereof extending transversely relatively to said crank-shaft, a crank-arm of dove-tail formation slidably mounted in said slot formed in the head, means upon the head for securing said crank- 55 arm in an adjusted position upon said head, a pivot-head pivotally mounted upon the outer end of said crank-arm operatively associated with said guide-bar for reciprocating the link when the crank-arm is rotated, 60 and means for rotating the crank-shaft.

7. A feeding device having in combination, a casing having inlet and discharge openings, 70 an inlet pipe connected with said casing, a material treating machine to which the inlet pipe is connected, blades movably mounted within the casing located in spaced relation to each other forming a passageway for the material to pass between said blades, shafts located adjacent to said inlet pipe upon which the ends of the blades are secured, arms secured upon said shafts located without the casing, a link connecting 75 said arms, a guide-bar secured upon said link extending transversely thereto, a crank-shaft, a bearing associated with said casing 80 in which the crank-shaft is rotatably mounted, bearing bars located above and below the casing, shafts extending through said casing and pivotally mounted in said bearing bars, blades secured to the portions of said shafts located within the casing, arms secured upon said shafts, a link connecting said arms, and means for imparting a reciprocating motion to said link for oscillating the blades for distributing material throughout the width of 85 the outlet of the casing.

In testimony whereof I affix my signature.

WILLIAM D. WHITAKER.
